UNITED STATES PATENT OFFICE.

ADOLPH MARTIN MONDL, OF OSHKOSH, WISCONSIN.

AVIATION CAP.

Application filed February 7, 1935. Serial No. 7,547.

This invention relates to improvements in caps, and more particularly to aviation caps.

It is one of the objects of the present invention to provide a sheepskin lined, leather covered aviation cap which will fit perfectly.

A further object of the invention is to provide a cap of the class described which can be manufactured cheaply due to the fact that little material is wasted in cutting the cap blanks.

A further object of the invention is to provide a cap of the class described in which there are no visible V's to disturb the lines of seam, thereby making the cap neat and attractive in appearance and insuring a perfect fit thereof.

A further object of the invention is to provide an aviation cap which is of very simple construction, is strong and durable, and is well adapted for the purpose described.

With the above and other objects in view, the invention consists of the improved aviation cap and its parts and combinations as set forth in the claims, and all equivalents thereof.

In the accompanying drawing in which the same reference characters indicate the same parts in all of the views:

Fig. 1 is a view showing the patterns or blanks for the outer leather portion of the cap;

Fig. 2 is a similar view of the inner sheepskin lining of the cap; and

Fig. 3 is a perspective view of the improved cap.

Referring now more particularly to the drawing it will be seen that the improved cap is designated by the numeral 5. In general, the cap comprises an inner sheep-skin or fleece lining 6 and an outer leather covering 7.

The cap is designed to hug the head of the wearer closely and to attain that end, the cap sections are cut from patterns of a novel shape. Fig. 2 represents the patterns or blanks of one half of the lining of the cap and these blanks comprise members 8, 9, and 10, shaped as shown. The two pairs of complementary lining blanks are sewed together, said blanks being so shaped that when sewed together, a smooth, rounded shape results, and obviously, the lining comprises six sections. Fig. 1 represents the patterns or blanks of

one half of the outer layer of the cap and will be seen to include members 11, 12, and 13, shaped as shown, the blank 12 being elongated to form ear covering and a neck portion. The two pairs of complementary outer layer blanks are also sewed together and are sewed or otherwise secured to the completed lining and will correspond in finished shape exactly therewith, although the lines of seam of the sections will differ in position.

In the completed cap, the visible lines of seam are evenly positioned, one running from the center of the forehead to the rear of the cap, and the other seams being arc-shaped and equally dividing the side portions of the cap.

The completed cap is especially suited for aviators and is extremely warm and close and comfortable in fit. The sheep-skin lining is soft and warm and the finished leather outer layer lends an attractive, dressy appearance to the cap. The elongated portions of the members 10 and 12 cover the wearer's ears and can be secured about his chin, fastening means 14 being provided therein. Due to the peculiar shape of the lining and outer layer blanks, visible V's in the seams are eliminated, thereby making the cap neat in appearance and comfortable by eliminating bunching of any of the parts.

Referring more particularly to the configuration of the sections composing the outer layer of the cap, and the method of attaching the edges thereof together, it is well to further point out that the outer layer on each side of the cap is composed of three sections, said sections being similarly formed and connected together on opposite sides, and the layer on each side comprising what may be termed two end sections 11 and 13, and a central or intermediate elongated section 12, the latter having its opposite edges cut into rounded concave form, and having a downwardly projecting extension, and each end section having its opposite edges cut into rounded convex form, the inner rounded convex edge fitting the adjacent concave edge of the central section, and the said edges sewed together, the upper edge of the central section and the outer edges of the end sections on one side being sewed to the upper edge of the central section and to the outer edges of the end sections, respectively, on the

other side, and the two downwardly projecting extensions of the central sections, on opposite sides, forming flaps for covering the ears, and being carried around the chin of the wearer, the extremities thereof beneath the chin being provided with engageable fastening means 14, and with relation to the inner lining, it is well to further explain that said inner lining on each side is composed of the three connected together sections, comprising two end sections 8 and 9 and an intermediate section 10, said intermediate section having its upper portion of approximate cone-shape, and its lower portion reduced, with its upper cone-shaped portion lining substantially one-half of the central section of the outer layer of the cap and the reduced portion thereof lining the downwardly projecting ear flap of said central outer layer and one of the end sections 8 of the lining having its outer edge of rounded convex form and its lower edge of rounded concave form, said end section 8 of the lining on each side of the cap, extending across and underlying the upper portions of the outer layers of the cap on each side of said cap, and the other end section 9 of the lining on each side having rounded convex edges gradually tapering to a point, the inner of said rounded convex edges being sewed to the adjacent edge of the other end section or lining, and to the adjacent inclined edge of the intermediate section of the lining, and the outer inclined edge thereof, which occupies an outermost position, and also the upper rounded edge of the other end section 8 of the lining being sewed to corresponding edges of the complementary sections of the lining on the opposite side of the cap.

It will also be noticed that the sewing or stitch lines uniting the edges of the three sections of the inner lining, occupy a staggered relation with respect to the sewing or stitch lines of the outer layer of the cap.

It will be readily seen from the drawing and the foregoing description that the completed helmet will conform closely to the head of the wearer, and, when the downwardly-extending flaps are fastened under the chin, the head will be protected to the fullest extent. The strains incident to pulling the cap on and fastening the same will be distributed by the peculiarly-formed central side-pieces 12, so that there will be little or no objectionable strain on any of the seams; this is a very important feature in this device, as these helmets are required to be pulled into position quite strongly in view of the need for a close fit all around. On account of the downwardly-extending flaps or fastening-members which are formed integrally with these main side-pieces and which have sides that are curved or tapered to meet the lower edges of the adjacent pieces 11 and 13, there is a tendency to draw the lower edges of these pieces 11 and 13 against the head, so that a

comparatively few standard-size caps are sufficient to fit the majority of persons and also so that a particularly tight fit will be obtained against the forehead and cheeks. It has been found very difficult to make a helmet which will fit closely against the sides of the forehead and the cheeks, i. e., around the front opening in the helmet; and, therefore, this tight fitting at the front edges is a very desirable feature. In the helmets now in use, where there is usually more or less looseness around the face, the air enters when the aviator is going at high speed and the helmet is torn off the head or at least blown back to an uncomfortable position. This is obviated by my construction.

It is important that the depending extensions of the side pieces 12 shall be long enough to overlap under the chin and further that they shall be lined with a warmth-giving lining throughout their length, so that these extensions shall not only afford means for fastening the helmet to the head but shall also materially aid in keeping out the wind and keeping the throat warm. These advantages cannot be obtained by mere connecting straps. It is important also that the upper ends of the side pieces 12 shall widen out where they join on the median line of the helmet, so as to thereby not only provide a broad, strong connection between the opposite pieces (which are of course the strain-receiving pieces in the helmet), but also avoid the formation of peaks in the top of the helmet such as would occur by the use of a plurality of segmental sections meeting at their points at the top of the helmet.

It will be noted that changes may be made in the details of construction or shaping of the parts without departing from the scope of this invention; therefore, I don't wish to be limited to the exact construction herein shown and described except as specified in the following claims.

What I claim as my invention is:

1. A covering for the head having a closely-fitting portion formed of two front pieces, two side pieces and two rear pieces, the respective pairs being joined on a median line running fore-and-aft of the helmet, said side pieces extending downwardly to cover the ears and having integrally-formed projections for overlapping and fastening under the chin, said side pieces having concave side-edges for engagement with the corresponding convex side-edges of the adjacent front and back pieces, said side pieces being widened at their upper, joined edges.

2. A cap of the character set forth comprising an outer leather portion formed of oppositely-disposed pairs of front, intermediate and rear pieces joined on a median line running fore-and-aft of the helmet, the front pieces having extensions to form a central substantially V-shaped projection over the

forehead, the rear pieces extending well down over the back of the head, the intermediate pieces having concave side-edges for engagement with the convex side-edges of the 5 front and rear pieces and having downward-
ly-extending substantially V-shaped projections for fastening under the chin, and a lining having the same general shape as the outer portions secured thereto around the

edges only, the shape of the lower edges of 10 the pieces being such as to form unbroken lines or curves from the ends of the side extensions to the front and back of the cap, said intermediate pieces being widened at 15 their upper, joined edges.

In testimony whereof, I affix my signature.

ADOLPH MARTIN MONDL.
